UNITED STATES PATENT OFFICE.

HERBERT CORRALL, OF HELENSBURGH, AND JAMES HEGGIE, OF CLYDEBANK, SCOTLAND, ASSIGNEES TO THE SINGER MANUFACTURING COMPANY, OF ELIZABETH, NEW JERSEY, A CORPORATION OF NEW JERSEY.

LOOPER MECHANISM FOR SEWING MACHINES.

Application filed March 13, 1925, Serial No. 15,258, and in Great Britain March 26, 1924.

This invention relates to looper mechanism for glove and like sewing machines, adapted inter alia for attaching the thumb portions to gloves, of the type having a work-carrying pillar within which oscillates an upright looper spindle.

For the operations for which the machine is primarily intended there are employed twin needles confined to reciprocating movements in rectilinear paths and cooperating with a looper caused to oscillate in a path comprising arcs on opposite sides of the needle paths, the looper spindle receiving, in addition to its oscillatory movements, vibratory movements in a vertical plane perpendicular to the plane defined by the needles.

To avoid play or lost motion, the bearing for the looper spindle is fitted to a rocker mounted beneath the machine bed plate, said 20 rocker being formed at the end remote from the looper as a yoke to which is secured a lever bifurcated at both ends, said lever being housed within the standard of the machine frame and embracing at its upper end 25 an eccentric on the upper or needle-actuating shaft.

The looper spindle is of a length about half the length of the lever, so that, notwithstanding that only a minimum tilting movement is transmitted to the rocker, the required range of needle-avoiding movement is imparted to the looper.

In the accompanying drawings, Fig. 1 is an elevation of the working parts of a sewing machine constructed in accordance with the invention; Fig. 2 is a corresponding elevation at right angles to Fig. 1; Fig. 3 is a corresponding inverted plan; Fig. 4 is a fragmentary view showing the looper 30 spindle and looper; Fig. 5 is a detail view of a lever constituting an element of mechanism for tilting the looper spindle; Figs. 6, 7 and 8 are detail views of the looper to an enlarged scale; Fig. 9 is a plan of the work supporting pillar; Fig. 10 is a diagram illustrating in plan the needle paths and the path of the looper beak.

The machine shown comprises a frame of usual construction having a bed plate 1 hinged to one edge of a tray-like base 2, said base being formed integral with a receptacle 3 projecting from its forward edge adjacent to the stitch-forming mechanism. The receptacle 3 is fitted with a hinged lid 4 hav-

ing a depending bracket supporting a horizontal pin 5 on which is mounted a spool 6 of looper thread.

Journalled within the overhanging arm 7 of the machine frame is the main driving shaft 8 carrying at one end the usual band 55 wheel 9 and at the opposite end the crank disc 10 with crank pin 11 connected by a link 12 to a collar 13 adjustably clamped to the needle bar 14 carrying twin thread-carrying needles 15 and journalled for vertical reciprocator movements in the head of the machine arm 7.

The needles 15 cooperate with an oscillatory thread-carrying looper 16 supported by an upright looper spindle 17 substantially 60 aligned with the needles 15 and journalled in a non-rotable sleeve 18, said spindle 17 and sleeve 18 projecting upwardly through the bed plate 1.

The sleeve 18 is fitted tightly at its lower 70 end in an aperture in a rocker 19 through which projects the spindle 17, the latter carrying at its lower end a pinion 20.

The parts of the spindle 17 and of the sleeve 18 above the bed plate 1 are enclosed 75 within a divided tubular work-supporting pillar 21 of which one half is formed with the throat plate 22 provided with a needle aperture 23.

The rocker 19 is formed as a rigid structure mounted on pintles 24 beneath the bed plate 1, and is formed at the end remote from the looper spindle 17 as a yoke to which is secured at spaced points, as by screws 25, 26 on opposite sides of one of the pintles 24, 80 a lever 27 bifurcated at both ends, said lever 27 being housed within the standard of the machine frame and embracing at its upper end an eccentric 28 on the main shaft 8, the axis of which is parallel to the pintles 24.

The screw 26 penetrates an elongated slot 29 in the lever 27. A screw 30 provides a means of adjustment of the position of the screw 26 in the slot 29.

The looper spindle 17 is of considerable 100 length, say about half the length of the lever 27, so that, notwithstanding that only a minimum rocking movement is transmitted to the rocker 19, the required range of needle-avoiding movement is imparted to the 105 looper 16, the spindle 17 being vibrated in a plane perpendicular to the shaft 8.

The looper 16 comprises an arcuate blade

integral with a shank 31 and with a ring 32 embracing and fixed to the looper spindle 17.

Fixed to the shank 31 beneath the looper blade is a looper thread deflector in the form 5 of a scoop coaxial with the spindle 17 presenting cam edges comprising a convexly curved edge 33 engageable with the looper thread *b* in the forward movement of the looper and a concavely curved edge 34 engageable with the said thread on the retreat of the looper.

The pinion 20 meshes with a toothed sector 35 journalled on a pivot 36 fixed to an arm of the rocker 19 and connected by a pitman 37 with a crank 38 on an upright shaft 39 housed within the standard of the machine frame and connected by mitre gears 40, 41, with the shaft 8, whence the spindle 17 derives oscillatory movements.

20 42 denotes the presser or feed foot of usual construction and arrangement. 43 denotes a thread guiding eyed member on the needle bar cooperating with the stationary adjustable eyed member 44 in taking up the needle- 25 threads *a*.

As in prior construction, to afford access to the looper, the half of the tubular pillar 21 fitted with the throat plate 22 is swung on the pivot 45 by manipulation of the 30 lever 46.

As will appear from the foregoing, the needles 15 are confined to movement in vertical paths, while the looper 16 oscillates in a path comprising arcs on opposite sides of the 35 needle paths, as best seen in Fig. 10. To effect transition from one to the other of said arcs there are positively imparted to the looper spindle 17 vibratory movements in a vertical plane perpendicular to the plane defined by the needles 15, said vibratory movements being derived from the eccentric 28 acting on the lever 27, the movements of which latter are transmitted to the rocker 19.

What we claim is:—

45 1. A sewing machine having a frame comprising a bed, tubular work-supporting pillar and overhanging bracket-arm members rising from said bed, a looper-spindle disposed longitudinally of and within said work-supporting pillar, a support in which

said looper-spindle is journaled, said support being mounted to rock on an axis parallel to said bed, a reciprocating needle, a needle driving shaft, and actuating connections extending downwardly within said bracket- 55 arm for rocking said looper-support and for oscillating said looper-spindle.

2. In a sewing machine having a frame including a bed plate, a looper spindle projecting upwardly through the bed plate, a needle-driving shaft above the bed plate, an actuating member on said shaft, a structure beneath the bed plate mounted to rock on an axis parallel to said shaft, said structure sustaining the lower end of said spindle, connections between said shaft and said spindle for oscillating said spindle, and a connection between said actuating member and said structure for imparting rocking movements to said structure and thereby vibrating said 70 spindle in a plane perpendicular to said shaft.

3. In a sewing machine in combination with a reciprocating needle and a cooperating looper, a looper spindle substantially 75 aligned with said needle, a needle-driving shaft, an eccentric on said shaft, two pintles on a line parallel with said shaft, a rocker mounted between said pintles, said rocker sustaining said looper spindle, and a lever 80 engaged by said eccentric and having connections with said rocker on opposite sides of one of said pintles.

4. In a sewing machine, in combination with a reciprocating needle, an oscillatory 85 looper spindle substantially aligned with said needle, a looper comprising a blade and a shank and a ring integral with said blade, said ring fixed to said spindle, a looper thread deflector in the form of a scoop having cam edges participating in the oscillatory movements of said looper, a needle-driving shaft, and connections between said shaft and said spindle for oscillating said 90 spindle and for vibrating said spindle in a 95 plane perpendicular to said shaft.

In testimony whereof we have signed our names to this specification.

HERBERT CORALL.
JAMES HEGGIE.
